CLAIM

The ornamental design for a razor, as shown and described.

DESCRIPTION

FIG. 1 is a rear elevational view of a razor showing my new design;

FIG. 2 is a right side elevational view thereof;

FIG. 3 is a front elevational view thereof;

FIG. 4 is a left side elevational view thereof;

FIG. 5 is a bottom plan view thereof; and

FIG. 6 is a top plan view thereof;

FIG. 7 is a rear elevational view showing a second embodiment of my new design;

FIG. 8 is a right side elevational view thereof;

FIG. 9 is a front elevational view thereof;

FIG. 10 is a left side elevational view thereof; and,

FIG. 11 is a bottom plan view thereof.

The partial color hatching is understood to continue throughout the surface of the razor except for the portions shaded in black.
